L. C. DOANE

LIGHTING FIXTURE

Filed Sept. 6, 1920

FIG. 1.

FIG. 5.

FIG. 2.

FIG. 3.

FIG. 4.

INVENTOR:

LEROY C. DOANE,

BY

John G. Wren

HIS ATTORNEY.

UNITED STATES PATENT OFFICE.

LEROY C. DOANE, OF CLEVELAND, OHIO, ASSIGNOR TO GENERAL ELECTRIC COMPANY,
A CORPORATION OF NEW YORK.

LIGHTING FIXTURE.

Application filed September 8, 1920. Serial No. 408,909.

To all whom it may concern:

Be it known that I, LEROY C. DOANE, a citizen of the United States, residing at Cleveland, in the county of Cuyahoga, State of Ohio, have invented certain new and useful Improvements in Lighting Fixtures, of which the following is a specification.

My invention relates to lighting fixtures and more particularly to lighting fixtures of the enclosed type.

My object is to produce a totally enclosed lighting unit in which the incandescent lamp is readily accessible for replacement or removal without the necessity of removing the reflector or shade. This object is accomplished by supporting the reflector so that it may be raised to expose the incandescent lamp through an aperture in the bottom of the reflector and in normally closing the aperture when the reflector is in a lowered position with a quickly detachable cover. Other advantages will be apparent from the appended specification to those skilled in the art.

My invention will be more fully understood by referring to the accompanying drawing in which Fig. 1 is an elevation partially in section of a lighting fixture embodying my invention; Fig. 2 is an enlarged plan and elevation view of a spring clip used in connection with the fixture of Fig. 1; Fig. 3 is a modification of the fixture supporting means; Fig. 4 is an enlarged fragmentary elevation of a detail thereof; and Fig. 5 is a plan view of a detail of the device shown in Fig. 3.

Referring to Figs. 1 and 2 of the drawing, the ceiling plate 10 has attached thereto the flexible cord 11, which contains the current carrying wires, by means of the wedging clamps 12 and 13 and the rubber gasket 14. The clamp 12 is supported from the inner side of the ceiling plate 10 and receives the rubber gasket 14 between its wedging surface 15 and the flexible cord 11. The clamp 13, which is on the outside of the ceiling plate 10, screws onto the protruding portion of the clamp 12 and receives the gasket 14 on its wedging surface 16 so that when the clamp 13 is screwed onto the clamp 12 the rubber gasket 14 is tightly compressed against the flexible cord 11 by the wedging

surfaces 16 and 15 respectively so as to prevent the movement of the cord 11 relative to the clamps 12 and 13 which are in turn located on the ceiling plate as described.

On the lower end of the cord 11 is fastened a cap 17 by means of its wedging surface 18, the rubber gasket 19 and the wedging surface 20 of the clamp 21 which is screwed onto the upper end of the cap 17, the action being similar to that of the clamps 12 and 13 and the gasket 14. A nipple 22, which is screwed into the under side of the cap 17 around the cord 11, supports the lamp socket 23 by being screwed into the metal cap 24 on the upper end thereof. An internal threaded portion 25 on the lower edges of the cap 17 receives the threaded upper end of the canopy 26.

The canopy 26 terminates at the lower end in a flare 27 which supports the member 28 which can be slid up around the canopy 26. The member 28 has a series of fingers 29 which are sprung over the heel 30 of a glass reflector 31 and in conjunction with the flare 27 of the canopy 26, serves to support the reflector 31 as well as provide a substantially dust proof cover for the end of the reflector. An aperture 32 in the lower surface of the reflector 31 is sufficiently large to permit the passage therethrough of an incandescent lamp 33 which is inserted in the socket 23. The aperture 32 is covered by a conical plate 34 held in place by the action of the spring clip 35 whose opposite ends rest on the edge of the aperture. A nut 36 attached to the center of the clip 35 receives the bolt 37 whose shank 38 slides through the tip of the conical plate 34 and whose head 39, in the shape of an ornamental tassel, rests against the tip of the plate.

A projection 40, caused by a notch near each end of the spring clip 35, slides on the inner surface of the conical plate 34 to give clearance to the edge of the aperture 32 between the end of the clip and the inner surface of the conical plate 34. The conical plate 34 may be removed from the aperture 32 of the reflector 31 by withdrawing the head 39 from the tip of the plate 34 which action causes the spring clip 35 to be drawn down into the conical plate 34 and so releases the edge of the aperture 32 from engagement

with the ends of the spring clip 35. By reversing the operation, the plate 34 is placed over the aperture 32.

To insert or remove an incandescent lamp 33, the conical plate 34 is removed as just described and the reflector 31 is raised, the member 28 sliding up the canopy 26 and the lamp 33 passing through the aperture 32 of the reflector as shown in the dotted lines 10 of Fig. 1. When the lamp 33 has been replaced, the reflector is lowered until the member 28 rests on the flare 27 of the canopy 26. The conical plate 34 is then replaced over the aperture 32. The unit is 15 preferably assembled by placing the clamp 21, rubber gasket 19 and cap 17 over the lower end of the flexible cord 11 and fastening them together so that the cord 11 supports the cap 17. The nipple 22 is then 20 inserted in the cap 17 and the lamp socket 23 attached thereto. The member 28 is then slipped over the heel 30 of the reflector 31 and the canopy 26 is inserted through the aperture 32 of the reflector and is engaged 25 with the member 28 which slides down the canopy until the member 28 rests upon the flange 27 of the canopy. The upper end of the canopy 26 is then brought into engagement with the threaded portion 25 of 30 the cap 17. The reflector 31 is then raised about the canopy 26, an incandescent lamp 33 is inserted in the socket 23 and the reflector is again lowered. The head 39 of the bolt 37 is withdrawn from the tip of the 35 conical cover plate 34 and the cover plate placed over the aperture 32 in the reflector, the head 39 being released to permit the ends of the spring clip 35 to engage the edges of the aperture 32. In the drawing 40 the reflector 31 is shown as having a clear upper surface and enameled sides and lower surface.

In Figs. 3, 4 and 5, I have shown a modification in which the canopy 41 is attached to the socket cap 42 of the lamp socket 43 and the assembly of the complete unit is made more readily and more conveniently. In this case the metal cap 42 of the socket 43 is provided with three radial projections 44 which engage three similar recessed slots 45 in the upper end of the canopy 41. A spring 46, which bears against the cover cap 47 carried on the threaded extension 48 of the socket cap 42 and against a washer 49 resting on the upper end of the canopy 41, tends to retain the projections 44 in the recess of the slots 45. The canopy 41 is released by pressing upwardly and turning the canopy to bring the radial projections 44 out of engagement with the recess of the slots 45. A ring 50, which screws into the threaded extension 48, is used to support the fixture although a conduit may be used.

In the case of the modification, the assembly of the unit is preferably made as fol-

lows. The washer 49 is placed against the cap 42 of the socket 43, the spring 46 is placed around the threaded extension 48 and on the washer 49 and the ornamental cap 47 is then screwed on the threaded extension. The threaded extension 48 may now be attached to the supporting ring 50 or to conduit. The member 28 is sprung over the heel 30 of the reflector 31 as before and the canopy 41 passed 70 through the aperture 32 of the reflector to engage the member 28 which is brought to rest against the flare 27. The canopy 41 is now passed over the socket 43 against the washer 49 to compress the spring 46 75 and bring the recessed slots 45 into engagement with the projections 44. The canopy is then turned slightly to place the projections 44 in the recesses of the slots 45. The canopy and reflector are now supported 80 and the reflector is raised, a lamp is inserted in the socket 43, the reflector is lowered and the conical plate 34 is placed over the aperture as before.

What I claim as new and desire to secure 85 by Letters Patent of the United States, is:—

1. In a totally enclosing lighting fixture, the combination of a lamp socket, means for supporting said socket, a lamp in said socket, a canopy supported by and enclosing 90 said socket, a reflector or shade, a member engaging said reflector or shade and slidably supported on said canopy, an aperture in the lower surface of said reflector or shade sufficiently large to provide clearance for said 95 lamp and means for closing said aperture comprising a substantially conical cover, a spring clip attached to said cover and engaging the edges of said aperture and means for drawing said spring clip into said conical cover to disengage the edges of said aperture.

2. A lighting fixture comprising a globe, an incandescent electric lamp within said globe, a socket for said lamp, a member surrounding said socket and extending through an opening in said globe to slidably support the latter, said globe having another opening substantially in alignment with said lamp and of sufficient size to permit the globe 100 to be moved over said lamp, and a closure for said last mentioned opening.

3. In a lighting fixture, the combination with a socket for an electric incandescent lamp and a support therefor, of a globe disposed to surround the lamp and having upper and lower openings, the latter opening being sufficiently large to allow the passage therethrough of the lamp, a closure for said lower opening and a spring member 105 engaging the inner surface of the bottom of said globe for retaining said closure in position.

4. In a lighting fixture, the combination with a socket for an electric incandescent 110

lamp and a support therefor, of a globe disposed to surround the lamp and having upper and lower openings, the latter opening being sufficiently large to allow the passage 5 therethrough of the lamp, a closure for said lower opening of sufficient diameter that its edges fit tightly against the outer surface

of the bottom of said globe and a spring member engaging the inner surface of the bottom of said globe for holding said closure 10 in position.

In witness whereof, I have hereunto set my hand this third day of September, 1920.

LEROY C. DOANE.
